UNITED STATES PATENT OFFICE.

JOHN G. FRIBERG, OF MAIDEN ROCK, WISCONSIN.

NECK-PAD.

1,101,425.

Specification of Letters Patent.

Patented June 23, 1914.

Application filed June 21, 1913. Serial No. 775,090.

To all whom it may concern:

Be it known that I, JOHN G. FRIBERG, a citizen of the United States, residing at Maiden Rock, in the county of Pierce and

5 State of Wisconsin, have invented new and useful Improvements in Neck-Pads, of which the following is a specification.

This invention relates to neck pads for harness collars, and it has particular reference to the means for adjustably connecting the pad with the collar, the object being to enable collars of various sizes to be used.

10 A further object of the invention is to simplify and improve the means whereby 15 the pad is connected with the collar.

With these and other ends in view which will readily appear as the nature of the invention is better understood, the same consists in the improved construction and novel 20 arrangement and combination of parts which will be hereinafter fully described and particularly pointed out in the claims.

In the accompanying drawing has been 25 illustrated a simple and preferred form of the invention, it being, however, understood that no limitation is necessarily made to the precise structural details therein exhibited, but that changes, alterations and modifications within the scope of the claims may be 30 resorted to when desired.

In the drawing,—Figure 1 is a top plan view of the improved pad, showing also portions of the collar. Fig. 2 is a side elevation. Fig. 3 is a vertical sectional view 35 taken on the line 3—3 in Fig. 1. Fig. 4 is a transverse sectional view taken on the line 4—4 in Fig. 1. Fig. 5 is a transverse sectional view taken concentrically through the pad on the line 5—5 in Fig. 1. Fig. 6 is a 40 perspective detail view, showing a portion of the pad and a portion of the collar adapted to be connected therewith.

Corresponding parts in the several figures 45 are denoted by like characters of reference.

The improved pad comprises a body portion 10 which may be made of leather or other suitable material of sufficient strength and flexibility for the purpose. Secured on the upper face of the body member 1 is a 50 metallic plate 11 having upstanding prongs 12 disposed along the longitudinal medial line thereof. A cushion member 13 of felt or like material is provided, the same having fastening means, such as straps and buckles 14, 15, whereby it may be operatively 55 connected with the body member 10, which

latter is preferably provided with apertures 16 for the passage of one or more of the straps 14.

17 is a top flap which constitutes a connecting member for the side members 18 of the collar. Said top flap which may be made of leather or other suitable flexible material and which may be strengthened and reinforced in any desired manner is provided with apertures 19 engaging the upstanding prongs 12. Said top flap is also provided with rows of perforations 20 extending through the length thereof, said perforations being suitably spaced and the 60 perforations in the several rows (two such rows having been shown) are disposed in transverse alinement.

Each side member 18 of the collar is provided adjacent to its upper end with metallic 65 hook members 21 which are of the construction best seen in Fig. 6, each of said hook members comprising a base plate 22 on the collar and from which the hook 21 extends upwardly, the bill of the hook being curved 70 outwardly and downwardly and rounded at its extremity to provide a smooth surface. Each hook is also provided with a transverse eye 23.

In assembling the parts of the improved 75 device, it will be seen that the cushion member is connected with the body member by the straps and buckles, and that the top flap is retained in position by the upstanding prongs 12 which project therethrough and 80 also by the straps and buckles beneath which the said top flap is guided. The prongs 12 extend through the central portion of the top flap, the ends of which project laterally, and the side members of the 85 collar are connected with the top flap by means of the hooks 21 which may be placed in engagement with perforations at various 90 distances from the prongs 12. It will be evident that by moving the hooks outwardly 95 with respect to the prongs the dimensions of the collar will be increased, and vice versa. To prevent accidental disengagement of the hooks 21 from the perforations 20, a tongue 100 24 may be passed through the eyes of the 105 hooks at either side of the device.

Having thus described the invention, what is claimed as new, is:—

1. A neck pad for harness collars comprising a flexible body member, a rigid plate 110 secured thereon and having upstanding prongs, a cushion pad having straps and

buckles engaging the body member, a top flap having apertures engaging the upstanding prongs, said top flap being positioned beneath the straps and buckles and provided with rows of perforations, and collar members having hooks engaging the perforations in the top flap.

2. A neck pad for harness collars comprising a flexible body member, a rigid plate secured thereon, a cushion pad having straps and buckles extending across the body member, and a top flap connected with the rigid plate, said top flap being positioned beneath the straps and buckles and provided with

rows of perforations, in combination with 15 collar members provided with upwardly extending outwardly and downwardly curved hooks having transverse eyes, said hooks engaging perforations in the top flap, and a tongue extending through the eyes of the 20 hooks.

In testimony whereof I affix my signature in presence of two witnesses.

JOHN G. FRIBERG.
